UNITED STATES PATENT OFFICE

143,718

DESIGN FOR A FRAME FOR PORTABLE CONVEYER

Earl H. Ensinger, Cleveland, Ohio

Application August 1, 1945, Serial No. 121,130

Term of patent 14 years

(CL. D55—1)

To all whom it may concern:

Be it known that I, Earl H. Ensinger, a citizen of the United States, and residing at Cleveland, in the county of Cuyahoga and State of Ohio, have invented a new, original, and ornamental Design for a Frame for Portable Conveyer, of which the following is a specification, reference being had to the accompanying drawing, forming a part thereof, wherein:

Figure 1 is a side perspective view of a frame for portable conveyer, embodying my new design; and

Figure 2 is a perspective view of the other side thereof.

I claim:

The ornamental design for a frame for portable conveyer, substantially as shown.

EARL H. ENSINGER.
